(57) **CLAIM**

The ornamental design for a finger ring interior, as shown and described.

DESCRIPTION

FIG. 1 is a perspective view of a finger ring interior; FIG. 2 is a perspective view of a second embodiment of FIG. 1; and,

FIG. 3 is an enlarged top view of FIG. 1, the bottom view is a mirror image.

In the Figures, the ring exterior (that is, the portion of the ring shown in FIG. 1 as a smooth outer surface of a cylindrical cross-section, in FIG. 2 as bearing gemstones and an annular groove, and FIG. 3 as a phantom line) is for illustrative purposes only and forms no part of the claimed design.
